UNITED STATES PATENT OFFICE.

JAMES H. LANCASTER, OF NEW YORK, N. Y.

DESIGN FOR A CYCLE-LAMP.

SPECIFICATION forming part of Design No. 31,318, dated August 1, 1899.

Application filed April 14, 1899. Serial No. 713,062. Term of patent 3½ years.

To all whom it may concern:

Be it known that I, JAMES H. LANCASTER, a citizen of the United States, and a resident of New York, in the county of New York and 5 State of New York, have invented and produced a new and original Design for a Cycle-Lamp, of which the following is a specification.

The drawing hereto attached is a view in perspective of a lamp embodying my design.

10 As shown in the drawing, the leading or material features of my design consist of a water-supply chamber A, placed above and connected by a neck to the body B of the lamp, and a reflector or combustion chamber D.

15 The body B is cylindrical in form, terminating in a cup-shaped device F with annular beads f. Around the upper or head portion g of the body are a plurality of beads or corrugations arranged on an incline, as shown.

20 The water-supply chamber is cylindrical and nearly spherical in form, with an encircling central bead a, suitably milled. This water-chamber is connected to the body of the 25 circular neck H, provided with annular beads h, as shown.

The circular disk E shown on the center of

the neck represents the face or surface of a handle of a valve or cock.

The combustion or flame chamber D is of 30 cylindrical form, having a diverging or flaring outer edge d and chimney P. The surface of the cylindrical portion is pierced with small apertures on both sides above and below the jewels N. The chimney has an upwardly and 35 outwardly perforated flaring neck p, a head p², formed as a vertical continuation of said neck, and perforated cover-plate p³, seated upon said head and concavo-convex in form.

The filling-cap J of the water-chamber is 40 milled around the edge.

The reflector is supported on one side and close to the body of the lamp by side brackets O O.

What I claim is—

45 The design for a cycle-lamp, substantially as shown and described.

Signed at New York, in the county of New York and State of New York, this 13th day of April, A. D. 1899.

JAMES H. LANCASTER.
